UNITED STATES PATENT OFFICE.

WILLIAM C. HUNT, OF TORONTO, ONTARIO, CANADA.

DESIGN FOR A COMBINED PHONOGRAPH AND ADVERTISING CABINET.

Application filed March 27, 1922. Serial No. 1,401. Term of patent 3½ years.

To all whom it may concern:

Be it known that I, WILLIAM C. HUNT, a subject of the King of Great Britain, residing in the city of Toronto, county of York, Province of Ontario, Canada, have invented a new, original, and ornamental Design for a Combined Phonograph and Advertising Cabinet, of which the following is a specification, reference being had to the accompanying drawing, forming part thereof,

which is a front elevation of my improved cabinet.

I claim:

The ornamental design for a combined phonograph and advertising cabinet, as shown.

Signed at Toronto, Canada, this 21st day of March, 1922.

WILLIAM C. HUNT.
